ELECTRIC TRANSLATING CIRCUIT

Robert B. Dome, Bridgeport, Conn., assignor to
General Electric Company, a corporation of
New York

Application March 11, 1941, Serial No. 382,701

10 Claims. (Cl. 179—171.5)

My invention relates to signal transmission systems, and more particularly to systems for transmitting signals having frequencies extending over wide frequency bands with minimum distortion.

It is frequently desirable to transmit such signals from a source to a utilization device therefor, when the source and the utilization device have different impedances. As an example, it is often desired to transmit signals from a modulating electron discharge device to a modulated carrier wave amplifier. As is well known, for the transfer of maximum energy from a source to a utilization device, the two should have the same impedance. Usually, however, the impedance of a modulating electron discharge device differs from the impedance of the associated modulated carrier wave amplifier, with the result that less than the maximum possible amount of energy is transferred from the modulating device to the amplifier, and, which is worse in many situations, the transmission time of signals passing between the modulating discharge device and the amplifier varies widely at different signal frequencies, resulting in undesirable distortion. Although transformers may be used to provide impedance matching in some cases, many situations arise where satisfactory transformers either cannot be constructed, or are difficult to produce, as when the frequency band to be transmitted is extremely broad.

It is an object of my invention to provide improved means for transmitting signals having frequencies extending over a wide band between circuits of different impedance, while maintaining the signal transmission time substantially constant over the frequency band.

It is a further object of my invention to provide such an improved transmitting means in which the ratio of input to output voltage is substantially constant over the frequency band.

It is highly advantageous to utilize such transmitting means in television apparatus for transferring video signals between circuits having substantially different impedance. Such video signals may have frequencies extending over a band of frequencies as much as four or more megacycles wide, for which transformers cannot be constructed and, if the phase shift between input and output of the transmitting means does not change substantially linearly with respect to frequency over the band, serious distortion may be produced. Such a transmitting means is, in particular, useful for transferring video signals from a detector circuit, which usually is of low

impedance, to a following amplifier circuit, which usually is of high input impedance, or from a video modulator to a power amplifier.

The addition to a modulating electron discharge device, of means for insuring that the time of transmission of low frequency signals to the accompanying modulated amplifier is constant, tends to lower the impedance of the modulating electron discharge device, so that an even greater difference exists between the impedance of such a modulating electron discharge device, compensated for low frequency signals, and the input impedance of an accompanying modulated amplifier.

15 It is accordingly a further object of my invention to provide suitable means for transferring video signals from such a modulating electron discharge device, compensated for low frequency signals, to an accompanying carrier wave amplifier, while maintaining the signal transmission time and the ratio of input to output voltage through the transfer means substantially constant over the band of frequencies.

25 The features of my invention which I believe to be novel are set forth with particularity in the appended claims. My invention itself, however, both as to its organization and manner of operation, together with further objects and advantages thereof may best be understood by reference to the following description taken in connection with the accompanying drawing in which Fig. 1 illustrates one embodiment of my invention, Figs. 2 and 3 include curves representing certain characteristics of my invention, 30 Fig. 4 is another embodiment of my invention, and Fig. 5 includes curves representing further characteristics of the device of Fig. 1.

In Fig. 1 a balanced power amplifier, including 35 electron discharge devices 10 and 11, is supplied with radio frequency oscillations from a source, not shown, and transmits the amplified oscillations to antenna 12. Operating potential for the devices 10 and 11 is supplied from a source 13 of potential through a modulating inductance 14, the potential across which is modulated by an electron discharge device 15 in response to signals from a second source, not shown, from which the device 15 is energized. Such apparatus is useful for the transmission of signals, such as 40 television signals. The signals amplified through the discharge device 15 are video signals, and the oscillations amplified through the devices 10 and 11 are high frequency carrier oscillations.

45 The balanced power amplifier including the devices 10 and 11 is of usual construction. The

input circuit includes an input transformer 16, energized from the source, not shown, and whose secondary is connected between the control electrodes 17 and 18 of the discharge devices 10 and 11. The cathodes of these two devices are connected to ground, and through a resistance 19 in shunt to a condenser 20 to the central point of the secondary of transformer 16. The output circuit of the discharge devices 10 and 11 includes an inductance 21 connected between the anodes 22 and 23 of the discharge devices. A condenser 24 is connected in shunt to the inductance 21 to form a circuit tuned to the frequency of oscillations impressed on the discharge devices 10 and 11 through the transformer 16.

Neutralization is provided in this power amplifier by two condensers 25 and 26, the first being connected between the anode 22 and control electrode 18, and the second being connected between the anode 23 and the control electrode 17. An inductance 27, connected between the antenna 12 and the ground, is coupled to the inductance 21 to transfer oscillations amplified through the power amplifier to the antenna 12 for radiation therefrom.

The source 13, as mentioned above, supplies operating potential for the discharge devices 10 and 11, its negative terminal being grounded and its positive terminal being connected through the inductance 14 and an inductance 28 to the center point of the inductance 21. The purpose and character of the inductance 28 will be described later.

In order to modulate the potential across inductance 14 in response to signals from discharge device 15, the cathode 29 of the device 15 is connected to ground, and the anode 30 thereof is connected to a point between the inductances 14 and 28. Signal voltages from the second source mentioned above are impressed between the control electrode 31 of the discharge device 15 and ground.

When no signal is applied to the control electrode 31, a constant potential is supplied from the source 13 to the discharge devices 10 and 11, and the intensity of radiation from the antenna 12 is constant. When signals from the second source are applied to the control electrode 31, current flowing through the cathode 29 and anode 30 of the discharge device 15 varies in response thereto, so that the potential across inductance 14 varies, and consequently the potential supplied to the discharge devices 10 and 11 from the source 13 varies in response to such signals. As a result the amount of amplification through the discharge devices 10 and 11 varies in response to the signals, and the intensity of radiation from the antenna 12 varies likewise.

In order to limit to a small value the amount of signal current passing through the inductance 14, and being thereby shunted around the power amplifier, the inductance 14 should be made to have several times the impedance, at the frequency of the lowest frequency signal, of the load resistance represented by the power amplifier. A satisfactory value, for example, is twenty times the value of such load resistance.

Even though modulation is improved by the choice of a high value for the inductance 14, the transmission time of low frequency signal components through the discharge device 15 to the power amplifier may be undesirably greater than the transmission time of higher frequency components therethrough. This variation of transmission time with variation of signal frequency

at low frequencies may be satisfactorily compensated by the provision of a series combination of resistance 32 and condenser 33 in shunt to the inductance 14. At the lowest frequency for which uniform signal transmission time is desired, the reactance of the condenser 33 is made equal to one half the reactance of the inductance 14. In order to make the circuit wholly resistive at this lowest modulated frequency, the value of resistance 32 is made equal to half the reactance of the inductance 14 or equal to the reactance of the condenser 33 at this lowest signal frequency to be transmitted. The choice of such a value for resistance 32 results in the highest permissible value it can have, and still have zero transmission time of signals at the lowest frequency. That is, if a higher value of resistance were used, no value of capacitance could be found for condenser 33 which would yield zero transmission time.

While lower values of resistance may be used and still obtain zero transmission time by proper choice of values for condenser 33, this again is undesirable because the lower resistance absorbs more modulator power and thereby reduces its available power for the power amplifier. If for some compelling reason it is desirable to use a lower value of resistance, the condenser 33 should be correspondingly changed so that the capacity C of condenser 33 is equal to the inductance L of inductance 14 divided by two times the square of the resistance R of resistor 32, or

$$35 \quad C = \frac{L}{2R^2}$$

In Fig. 5, curve 34 illustrates the relation, when resistance 32 and condenser 33 are not connected in circuit, between the transmission time 40 of signals through the discharge device 15 to the power amplifier, plotted as ordinate, and the signal frequency, plotted as abscissa. Curve 35 illustrates the relation between the same factors, 45 when the resistance 32 and condenser 33, properly adjusted, are added to the apparatus. The curve 35 illustrates that transmission time is substantially constant as frequency changes, finally decreasing to zero, as signal frequency decreases from high values to a frequency of sixty cycles 50 per second.

In a particular television transmitter, which may be taken by way of an example, certain values assigned to various components are as follows to provide substantially constant transmission time from the modulating discharge device to the modulated amplifier at frequencies as low as 60 cycles. The load resistance of the power amplifier including discharge devices 10 and 11 may be 2490 ohms. The anode resistance of the discharge device 15 may be 900 ohms, the inductance 14 may be 132 henrys, the condenser 33, 0.107 microfarads, and the resistance 32, 24,900 ohms. The transmitter whose components have these values has a characteristic represented by curve 35.

It is well known that it is desirable, for the maximum transfer of power from a source to a load, to make the resistance of the source equal to the resistance of the load. Provision of such equality of resistance has also been considered desirable as an aid in providing constant transmission time of oscillations at all frequencies between such a source and load. Unequal phase shift, or transmission time, at different frequencies can be readily compensated for in such an

arrangement where the resistance of the source and the resistance of the load are equal.

The stray capacity to ground of a modulated amplifier, such as a power amplifier including the discharge devices 10 and 11, is usually different from the stray capacity to ground of a modulating electron discharge device, such as the device 15 and its associated circuits, and the associated resistances are also different. In general, it is found that in a circuit of this kind a low resistance is associated with a high capacity, and that a high resistance is associated with a low capacity. The reactance, and the impedance, of such a modulating discharge device and the associated modulated amplifier are generally different, making it difficult, if not impossible, to adjust the respective resistances of the modulated amplifier and the modulating discharge device to suitable values to obtain constant signal transmission time therebetween at all frequencies, while still keeping the modulation capability of the modulating discharge device high enough to modulate fully the power amplifier. If sufficient capacity be added to the modulated power amplifier, or to the modulator, whichever is the lower, to make the input and output capacitances equal in order to make it possible to adjust the apparatus for substantially constant signal transmission time at all frequencies, the ratio of signal voltage at the power amplifier to signal voltage at the modulating discharge device becomes too low at the upper frequencies of the signal. Such difficulties are overcome in accordance with my invention by the provision of the inductance 28 connected from the central point of the inductance 21 to a point between the anode 30 and the inductance 14, and the adjustment of the values of certain circuit constants.

The stray capacity to ground, associated with the modulating electron discharge device 15 and its associated circuits, is represented by a condenser 36, shown in dotted lines. The stray capacity to ground associated with the inductance 14, including the shunt resistance 32 and condenser 33, is represented by a second condenser 37, also shown in dotted lines. These stray capacities 36 and 37 are effective between the anode 30 and ground.

The modulated power amplifier including the discharge devices 10 and 11 also has various stray capacities associated with it, which are represented by a condenser 38, shown in dotted lines. This stray capacity 38 includes the anode to cathode, and anode to control electrode, capacity of each of the discharge devices 10 and 11, the neutralizing condensers 25 and 26, the stray capacity of the inductance 21 to ground, and the capacity of the associated wiring and condenser 24 to ground.

In a particular device, which is described as an example, the electron discharge devices 10 and 11 may be type 834 transmitting tubes. The capacity 38 in this device has a value of 25.6 micromicrofarads. It is desired to transmit television signals with this apparatus in which the upper limit of video frequencies to be transmitted is four megacycles. The reactance of the condenser 38 is 1560 ohms at this upper limit frequency. In accordance with my invention the resistance component of the load impedance, represented by the power amplifier including electron discharge devices 10 and 11, is made at least as low as the reactance of the stray capacity 38 of the power amplifier at the upper

limit frequency of the signals to be transmitted. The load resistance of the power amplifier is preferably made equal to 1560 ohms.

The effective load resistance of the power amplifier may be reduced to the desired value by connecting a resistance in shunt to the condenser 38. However, the use of such a resistance is not usually feasible or desirable. It is preferred to adjust the operating potential supplied to the power amplifier, while maintaining the anode current thereof at its maximum rated value by adjusting the coupling between inductances 21 and 27, until the resistance of the amplifier is of suitable value, equal to the reactance of the stray capacity at the upper limit frequency. By such adjustment of the anode potential of the amplifier, instead of using a shunt resistance, power loss in the shunt resistance is avoided, while no less power is radiated from the antenna 12.

To determine the necessary anode potential for the amplifier it is necessary only to know the maximum rated anode current for the discharge device, and to avoid operating the amplifier above its rated anode power dissipation. For the 834 type device, the maximum rated anode current is 100 milliamperes. A simple calculation according to Ohm's law indicates that a voltage of 312 volts across a load resistance of 1560 ohms produces a current of 200 milliamperes, which is the maximum rated current for two such discharge devices in parallel. It is, therefore, desirable to adjust the anode potential supply for the discharge devices 10 and 11 to 312 volts. The power supplied from the source 13 to the power amplifier is, therefore, 62.4 watts, and the devices are operating within their ratings.

In this particular apparatus two type 845 transmitting tubes in parallel are used, as the modulating electron discharge device 15. Because of the fact that two 845 type tubes can supply only 60 watts of power to the power amplifier, when the resistance of the power amplifier is 1560 ohms, the input to the devices 10 and 11 must be reduced to 60 watts, thereby making the required anode potential 306 volts for devices 10 and 11, and the total anode current 196 milliamperes. The load resistance of the amplifier is thus unchanged, being still 1560 ohms. The radio frequency output from the power amplifier under such conditions is about 36.6 watts.

Using such discharge devices in the particular apparatus, the sum of capacities 36 and 37 is found to be 47 micromicrofarads. With such a large value of stray capacity, it might be thought impossible to make the transmission time, and ratio of voltage applied to the power amplifier to voltage from the modulating device, substantially constant at all signal frequencies. The addition of the resistance 32 and the condenser 33 adds capacity to inductance 14 and increases the inequality of the stray capacities of the modulating discharge device and the modulated power amplifier, so as to make it appear even more impossible to make the transmission time, and voltage ratio constant.

The provision of the inductance 28 in accordance with my invention makes it possible to tolerate such widely unequal stray capacities, and still provide equal transmission time and voltage ratios at signal frequencies up to the upper frequency limits to be transmitted. The effective resistance of the discharge device 15 is adjusted to a value equal to the reactance of the sum of

stray capacities 36 and 37 at the upper frequency limit of the signals to be transmitted. Since, in the particular arrangement described, the sum of the stray capacities 36 and 37 is 47 micromicrofarads, as pointed out above, the reactance of these stray capacities 36 and 37 at the upper frequency limit of four megacycles is 850 ohms. In accordance with my invention, the equivalent anode resistance of the discharge device 15 is made 850 ohms. That is, the equivalent anode 10 resistance of the discharge device 15 is made equal to the reactance of all stray capacity associated with it at the upper frequency limit of desired signals, as is also done for devices 10 and 11. This may be readily done for the modulating amplifier by providing a controlled amount of negative, or degenerative, feedback in the modulator, as by the insertion of an adjustable cathode resistance 38, which as is well known by those skilled in the art, may be adjusted to change the dynamic plate resistance of the amplifier.

It is worthy of particular note that, in the adjustment and arrangement of any sort of apparatus according to my invention, the inductance 28 is utilized to separate the apparatus into two sections, in each of which the circuit resistance is made equal to the reactance of all circuit capacities at the highest frequency which it is desired to transmit.

In apparatus so adjusted, constant transmission time of oscillations of any frequency up to a high limit frequency, and a constant ratio of voltage in the two circuit sections, may be assured by provision of the inductance 28 with a value of reactance at the high limit frequency equal to half the sum of the resistances of the two sections of the apparatus on the two sides of the inductance 28.

In the particular apparatus, described above by way of example, the actual value of the inductance 28 is 48 microhenries. Its reactance at the upper limit frequency of four megacycles is 1205 ohms, being equal to the average of the resistance associated with device 15 and the resistance associated with devices 10 and 11.

The following equations express the circuit relations as set forth above:

$$R_1 = \frac{1}{2\pi f_0 C_1} \quad (1)$$

$$R_2 = \frac{1}{2\pi f_0 C_2} \quad (2)$$

$$2\pi f_0 L = \frac{R_1 + R_2}{2} \quad (3)$$

in which R_1 is the effective resistance in ohms of all apparatus, including discharge device 15, connected to the input side of reactance 28; R_2 is the effective resistance in ohms of all apparatus, including the power amplifier, connected to the output side of inductance 28; C_1 is the total stray capacity in farads, represented by condensers 36 and 37, of all apparatus connected to the input side of inductance 28; C_2 is the total stray capacity in farads, represented by condenser 38, of the apparatus including the power amplifier; L is the value of the inductance 28 expressed in henries; and f_0 is the limiting high frequency in cycles per second, up to which it is desired to transmit signals without distortion.

Having adjusted the various components of the apparatus to particular values in conformity with these relations, it may be shown that the trans-

mission time of signals from device 15 to the power amplifier, and the ratio of voltage supplied through the discharge device 15 to the voltage applied to the power amplifier, is substantially constant at all frequencies up to the limiting higher frequency f_0 .

$$\text{Let } Z_1 = j2\pi f L; Z_2 = \frac{-j}{2\pi f C_1}; \text{ and } Z_3 = \frac{-j}{2\pi f C_2}$$

In these equalities f represents signal frequency. The overall impedance of the power amplifier including stray capacity 38 is:

$$Z_4 = \frac{R_2 Z_3}{R_2 + Z_3} \quad (4)$$

Now the impedance of the power amplifier plus that of inductance 28 is:

$$Z_5 = Z_2 + Z_4 \quad (5)$$

If it be considered that the stray capacities 36 and 37 are effective between the resistance in the modulating discharge device circuit and the inductance 28, the impedance Z_5 , with the stray capacities 36 and 37 in shunt thereto, may be represented by the symbol Z_6 , and may be expressed as follows:

$$Z_6 = \frac{Z_2 Z_5}{Z_2 + Z_5} \quad (6)$$

The impedance across which the signal voltage appears, as it is transmitted through the discharge device 15, may be represented by the symbol Z , and may be expressed as follows:

$$Z = R_1 + Z_6 \quad (7)$$

The ratio of the voltage e_3 across C_1 to the effective signal voltage e_1 impressed across the impedance Z by the discharge device 15 is as follows:

$$\frac{e_3}{e_1} = \frac{Z_5}{Z} = \frac{Z_6}{Z_6 + R_1} \quad (8)$$

Now let e_2 represent the voltage applied across the impedance Z_4 of the power amplifier, and the ratio of e_2 to e_3 is:

$$\frac{e_2}{e_3} = \frac{Z_4}{Z_1 + Z_4} \quad (9)$$

To obtain the ratio of the output voltage e_2 , appearing across the power amplifier, to the input voltage e_1 to the apparatus, applied through the discharge device 15, Equations 8 and 9 may be multiplied, obtaining the following equation:

$$\frac{e_2}{e_1} = \frac{Z_4 Z_6}{(R_1 + Z_6)(Z_1 + Z_4)} \quad (10)$$

Equation 10 is the general network equation for apparatus to which my invention may be applied. In order to determine what results may be expected by the use of the particular values set forth hereinbefore for the components represented by the symbols R_1 , R_2 , C_1 , C_2 , and L , Equations 1, 2, and 3 may be substituted into Equation 10, eliminating the symbols L , C_1 , and C_2 to obtain the following equation:

$$\frac{e_2}{e_1} = \frac{R_2}{R_2 + R_1} \left[\frac{2}{2\left(\frac{l-f^2}{f_0^2}\right) + j\frac{f}{f_0}\left(3 - \frac{f^2}{f_0^2}\right)} \right] \quad (11)$$

Assigning an arbitrary value of unity to f_0 and also an arbitrary constant value less than unity to

$$\frac{R_2}{R_2 + R_1}$$

the relation between the voltage ratio e_2/e_1 , and the ratio of signal frequency f to the upper limit

frequency f_0 , may be readily plotted as a graph. The curve 40 in Fig. 2 represents this relation in which the voltage ratio e_2/e_1 is plotted as ordinate, and the frequency ratio f/f_0 as abscissa. Inspection shows that a substantially uniform voltage ratio exists for signals transmitted through a circuit adjusted in accordance with my invention up to a frequency ratio substantially greater than unity.

By comparison of the real and imaginary parts of the expression of voltage ratio in Equation 10, the phase relation ϕ between voltages e_2 and e_1 may be obtained, as follows:

$$\phi = \tan^{-1} \left[\frac{\frac{f}{f_0} \left(\frac{f^2}{f_0^2} - 3 \right)}{2 \left(1 - \frac{f^2}{f_0^2} \right)} \right] \quad (12)$$

Again assigning an arbitrary value of unity to f_0 , the relation between the phase angle ϕ and the ratio of signal frequency f to the upper limit frequency f_0 may be readily plotted. In Fig. 3 the curve 41 represents such a relation, in which the phase angle ϕ , expressed in radians, is plotted as ordinate; and the ratio of signal frequency f to upper limit frequency f_0 is plotted as abscissa. Inspection shows that a substantially uniformly increasing phase angle exists between the input voltage e_1 and the output voltage e_2 in apparatus arranged according to my invention, as the signal frequency increases through the band of frequencies within which undistorted signals are to be transmitted.

To obtain the transmission time t of a signal passing from the input to the output of a device arranged according to my invention, the following relation may be used:

$$T = \frac{\phi}{2\pi f} \quad (13)$$

The curve 42 of Fig. 3 represents the relation between transmission time T , determined by Equation 13 and expressed in seconds, plotted as ordinate (an arbitrary value of unity being again assigned to the upper limit frequency f_0), and the ratio of signal frequency f to the upper limit frequency f_0 , plotted as abscissa. Inspection shows that transmission time is substantially constant for all frequencies up to a frequency at least 20 per cent higher than the upper limit frequency f_0 .

If, instead of assigning an arbitrary value of unity to the upper limit frequency f_0 , it be assumed that the upper limit frequency f_0 is 4 megacycles, Equation 13 may be solved to find that the transmission time from input to output of a device adjusted in accordance with my invention is very nearly equal to 0.06 microsecond for signals of any frequency up to 4 megacycles. Further, the maximum transmission time for a signal of any frequency differs from the minimum transmission time for a signal of any other frequency within the assumed 4 megacycle range by only 0.0035 microsecond.

Although my invention has been described and illustrated as applied to apparatus for modulating a carrier wave in accordance with the intensity of a signal, it may be equally well applied to a power amplifier supplying signals to a load circuit which cannot easily be made to have the same resistance and reactance as the circuit associated with the power amplifier device. The requisite steps in applying my invention to such a power amplifier are the same as those followed in adjusting such a modulating

device as described above. The load circuit, whose resistance and reactance may not easily be made equal to the resistance and reactance of the power amplifier circuit, may be considered as being represented by the discharge devices 10 and 11, and their associated circuits, in Fig. 1. In other words, any suitable type of signal utilization circuit may be substituted for the carrier wave amplifier including discharge devices 10 and 11.

Then to adjust the device in accordance with my invention, the resistance 32 and condenser 33 with suitable values are added in shunt to the inductance 14. Next the resistance is made substantially equal, at the upper limit frequency of amplified signals, to the capacitive reactance in the power amplifier circuit including the discharge device 15. The same equality is provided in the utilization circuit including the discharge devices 10 and 11, and finally the reactance of the inductance 28 at the upper limit frequency of amplified signals is made equal to half the sum of the resistances in the power amplifier circuit and in the utilization circuit.

In Fig. 4 there is illustrated a portion of a television receiver which may be arranged according to my invention. In the figure a diode rectifier 50, acting as a second detector, is energized through a transformer 51 from a source, not shown, of intermediate frequency oscillations. These intermediate frequency oscillations may be modulated in intensity in accordance with video signals to be detected. A circuit is provided through which rectified current from the device 50 may flow. This circuit includes the device 50, the secondary of the transformer 51, an inductance 52, and a resistance 53, in order. A condenser 51, whose reactance is low at the frequency of the intermediate frequency oscillations transmitted through the transformer 51, but whose reactance is substantial at the frequency of video signals to be detected by the device 50, is connected in shunt to the inductance 52 and the resistance 53 to by-pass intermediate frequency oscillations therearound. The resistance 53, across which the detected video signals appear, is connected between the control electrode 54 and the cathode 55 of an electron discharge amplifying device 56 for amplification of video signals before their use.

In order to adjust this circuit including the second detector 50 and the input to the amplifying device 56 in accordance with my invention, three steps are necessary. The first step is to determine the total circuit resistance which is effective at the input side of the inductance 52. This resistance is composed almost entirely of the internal resistance of the diode rectifier 50. Having determined this total circuit resistance, the reactance of condenser 51 (which is regarded as including all stray capacity) is made equal to this resistance at the upper limit frequency of signals which it is desired to transmit to the amplifying device 56. This is done in accordance with Equation 1, given previously.

The second step requires the determination of the total circuit capacity effective at the output side of the inductance 52. That is, the circuit capacity effectively in shunt to the resistance 53 is determined. This circuit capacity is almost entirely stray capacity, primarily internal capacity of the discharge device 56 between the control electrode 54 and cathode 55. This total circuit capacity is represented in the drawing by a condenser 58, shown in dotted lines, con-

nected in shunt to resistance 53. The value of resistance 53 is made equal to the reactance of the condenser 58 at the upper limit frequency of signals to be transmitted. This step is in conformance with the requirements of Equation 2, given above.

The third step requisite to the adjustment of the device in accordance with my invention is to make the reactance of the inductance 52 at the upper limit frequency of signals to be transmitted equal to the average of the total circuit resistance on the input side of the inductance 52 and the total circuit resistance on the outside thereof. This step is in conformance with Equation 3, given above.

Having adjusted the circuit in accordance with Equations 1, 2, and 3, the result to be expected from the circuit may be determined by inspection of the curves 40, 41, and 42 in Figs. 2 and 3, as explained above in connection with the device of Fig. 1.

In general, my invention may be utilized with any apparatus for transmitting oscillations, such, for example, as video signal transmitting devices like those illustrated in the drawing, or other apparatus, such as two transmission lines of unequal surge impedance. Such apparatus may be arranged in accordance with my invention by following four steps. In the first step, it is necessary to separate the apparatus into two sections by placing an inductance therebetween, each of the two sections being capable of being represented electrically by a resistance and a capacity in shunt to each other.

The next step, after separating the two sections by the inductance, is to determine for one of the sections, so formed, the total value of circuit resistance, and the total value of circuit capacity. The reactance of the capacity at the upper limit frequency to be transmitted is calculated. It is then preferred that the resistance be adjusted, if convenient, until it is equal to this reactance. If it is inconvenient to adjust the resistance, the capacity may be adjusted to provide the desired equality, it usually being easy to add more capacity to the circuit to make the reactance at the upper limit frequency equal to the resistance. In any case, the reactance and resistance are made equal at the upper frequency limit.

In the third step the same process is carried out in making the resistance of the other section of the apparatus, on the output side of the inductance, equal to the reactance of the capacity in this other section at the upper limit frequency of the signals to be transmitted.

The fourth step is to adjust the reactance of the inductance, at the upper limit frequency to be transmitted, to be equal to the average value of the resistances in the two sections. When these four steps are properly carried out, constant transmission time and constant voltage ratio may be expected of signals transmitted between two such sections of the device, for signals of any frequency up to the upper limit frequency.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. In a transmission path for oscillations having frequencies extending over a band of frequencies having an upper limit frequency, an inductance separating said path into two sections, each of said sections having substantially equal effective resistance and capacitive reactance at said upper limit frequency, and said inductance having a reactance at said upper limit frequency substantially equal to half the sum of said resistances.

2. Apparatus for transmitting between two circuits oscillations having frequencies extending over a band of frequencies having an upper limit frequency with uniform gain at all frequencies in said band, and each of said circuits having resistance and capacity, the capacitive reactance and resistance in each of said circuits being equal at said upper limit frequency, and an inductance connected between said circuits having reactance at said upper limit frequency substantially equal to the average of said two resistances.

3. In a system for transmitting oscillations between a source and a load with uniform gain over a range of frequencies and with the same transmission time at all frequencies in said range, said source including an inductance, a resistor in series with a capacitance across said inductance proportioned to produce zero transmission time at a low frequency in said range, the capacitive reactance and resistance of both said load and said source including said inductance, resistor, and capacity being equal at a high frequency in said range, and an inductance between said source and load having reactance at said high frequency equal to the average of said resistances.

4. In a system for modulating oscillations from a source upon a carrier wave in a carrier wave amplifier, said source including an inductance connected to supply operating current to said amplifier, said oscillations from said source having frequencies in a predetermined range and being impressed across said inductance to vary such operating current, a resistor in series with a capacitance connected across said inductance and proportioned to produce zero transmission time of said oscillations at a low frequency in said range, the capacitive reactance and resistance of both said amplifier and said source including said inductance, resistor, and capacitance being equal at a high frequency in said range, and a second inductance connected between said source and said amplifier having reactance at said high frequency equal to the average of said resistances.

5. A signal transmission system for transmitting signals between a source and a load with uniform gain over a range of frequencies, said source including an inductance which tends to increase transmission time of signals at a low frequency in said range, and means to reduce signal transmission time at said low frequency comprising a resistance in series with a capacitance connected across said inductance, the resistance and the capacitive reactance of said capacitance being equal at said low frequency to half the reactance of said inductance.

6. In a system for transmitting oscillations between a source and a load with the same transmission time at all frequencies in a range of frequencies, said source including an inductance which increases transmission time of oscillations at a low frequency in said range, a resistance in series with a capacitance connected across said inductance, the inductance being equal to twice the product of the capacitance and the square of the resistance.

7. In a system for transmitting oscillations extending over a range, said system comprising an electron discharge amplifier having an output circuit including an inductance, a load circuit in shunt to said inductance, said inductance acting to increase transmission time of oscillations from said amplifier to said load at a low frequency in said range, and means to reduce transmission time of said oscillations at said low frequency comprising a resistance in series with a capacitance connected across said inductance, said resistance and the capacitive reactance of said capacitance each being equal to half the reactance of said inductance at said low frequency.

8. In a system for modulating oscillations from a source upon a carrier wave in a carrier wave amplifier, said source including an inductance connected to supply operating current to said amplifier, said source and said amplifier having resistance and reactance such that oscillations transmitted therebetween are subject to distortion at a predetermined high frequency, and means for minimizing such distortion comprising a second inductance connected between said source and said amplifier, the reactance of both said amplifier and said source including said first inductance being capacitive at said high frequency and equal to the respective resistance, and the reactance of said second inductance at said high frequency being made equal to the average of said resistances.

9. A signal transmission system comprising a source of signals having frequencies extending over a range, said source having output terminals,

an electron discharge device having terminals across which signals from said source may be impressed, said source and said device respectively having resistance and capacity between said terminals, whereby signals transmitted therebetween are subject to distortion at a predetermined high frequency in said range, the capacitive reactance and the resistance between both said input and said output terminals at said high frequency being equal, and means for transmitting signals from said output terminals to the terminals of said device with minimum distortion at said high frequency comprising an inductance having a reactance at said high frequency substantially equal to the average of said resistances.

10. In a signal transmission system comprising a source of signals having frequencies extending over a range of frequencies, a load circuit, the capacitive reactance tending to be unequal to the resistance at a high frequency in said range both in said source and in said load circuit whereby signals transmitted therebetween are subject to distortion at said high frequency, means producing equality between the resistance and capacitive reactance at said high frequency respectively in said source and said load circuit, and means for transmitting signals from said source to said load circuit with minimum distortion at said high frequency comprising an inductance having a reactance at said high frequency substantially equal to the average of the resistances of said source and said load circuit.
